UNITED STATES PATENT OFFICE.

FRITZ DÜRR, OF BERLIN, GERMANY.

VALVELESS TWO-CYCLE HYDROCARBON-MOTOR.

SPECIFICATION forming part of Letters Patent No. 625,387, dated May 23, 1899.

Application filed April 15, 1898. Serial No. 677,715. (No model.)

To all whom it may concern:

Be it known that I, FRITZ DÜRR, head engineer, a subject of the Emperor of Germany, and a resident of Berlin, in the Kingdom of 5 Prussia and Empire of Germany, have invented certain new and useful Improvements in Valveless Two-Cycle Hydrocarbon-Motors for Petroleum, Gas, Benzin, &c.; and I do hereby declare that the following is a full, clear, 10 and exact description thereof, reference being had to the accompanying drawings and to the letters of reference thereon.

My invention relates to a two-cycle or two-phase hydrocarbon-motor for petroleum, gas, 15 benzin, &c., which is adapted to work without constituent valve parts, so that an absolutely reliable and steady action can be guaranteed.

In this improvement the newly-sucked-up 20 supply of gas mixture remains in a telescopic movable explosion-chamber, in which also the ignition takes place, so that thereby the most perfect working is assured.

In the accompanying drawings, Figure 1 25 represents an axial section of my improved motor. Fig. 2 is a cross-section on the line 2 2, Fig. 1.

a represents a cylindrical casing, in which are inserted an upper cylinder *b* and a lower 30 cylinder *c*. The upper cylinder *b* is inserted from above the casing and the lower cylinder is inserted from beneath the casing, the lower cylinder being of much less diameter than the upper cylinder. The casing *a* and 35 the upper cylinder *b* are each formed with annular ribs *e* between them, whereby an annular space is provided, normally separated from the space *d* within the cylinders. The annular space is divided by radial ribs *f* into 40 segmental conduit-chamber *g* and segmental efflux-chamber *h*, as clearly shown in Fig. 2.

i is a piston common to both cylinders, having a tubular body surmounted by a mantle *i*'. The interior of the piston at the upper 45 end serves as the explosion-chamber and the lower end as a bearing for a connecting-rod *k*.

l is a cylindrical cover provided with a depending pipe *m*, having radial entrance holes or slots *n* at its upper end and which reaches 50 down right into the piston. Therefore the interior part of the piston slides telescopic-

ally onto the pipe *m*, and forms thereby the explosion-chamber, for the ignition of the gases takes place therein by an ordinary lighting contrivance. In the present case I 55 employ an electrical means for ignition, in which one of the poles *o* extends through the cover while being insulated therefrom and the other pole *r* is fastened in a partition *i*" in the piston *i* and is connected with a conductor *S* through the metal of the motor itself. The upper cylinder *b* is formed with radial ports *x*, connecting the conduit-chamber *g* with the space within the cylinders. The lower cylinder is formed with radial ports 65 *y*, providing communication between the space within the cylinders and the explosion-chamber. The upper cylinder is also formed with radial ports *z*, leading to the efflux-chamber *n*.

The operation of the motor is, as will now be described, as follows: Taking for granted that the motor is set in motion, so that as yet no gas mixture is contained therein, then when the piston *i* goes upward a little vacuum 70 is created in the space *d* until the ports *x*, joining the space *d* with the conduit-chamber *g*, are set free. At this moment the gas mixture which had been let into the conduit-chamber *g* flows at a great rate into the space 75 *d*. When the piston *i* again moves downward, then the new gas mixture is compressed in the space *d* until all the ports *y*, which are provided around the entire circumference of the lower cylinder *c* and the interior part of 80 the piston, exactly coincide. At this moment the compressed gas mixture flows through the ports *y* into the piston's interior *A* and the pipe *m* simultaneously, partly escaping through the openings or slots *n* into the cylinder interior *B*. At the next change of stroke on the one hand a vacuum is again formed in the space *d* and fresh gas mixture is admitted at 85 the end of the piston-stroke, and on the other hand the gas mixture in the working space *B* and the interior *A* of the piston is compressed and ignited by an electric spark as soon as 90 the poles *o* and *r* almost make contact or by any mode of ignition and so brings about an explosion. The exploding gas mixture now 95 does its work and drives the piston *i* downward, simultaneously, however, compressing 100

the gas mixture in the space d . Even before the ports y coincide the ports z in the right half of the cylinder b are set free by the upper edge of the piston, so that the burned 5 gases may escape into the efflux-chamber h . As soon as the discharging is started, the gas mixture, compressed in the space d , passes again through the ports y and again into the piston interior A and the same working procedure is repeated.

Having thus described my invention, the following is what I claim as new therein and desire to secure by Letters Patent:

- 15 1. A valveless two-cycle hydrocarbon-motor comprising the casing, the upper cylinder formed with supply-ports and efflux-ports and providing a conduit-chamber and an efflux-chamber in connection with the casing, the lower cylinder having ports and of less diameter than the upper cylinder, a piston having a tubular body surmounted by a mantle, telescoping the pipe, and formed with ports adapted to coincide with the ports in the lower cylinder, and an igniting 20 means connected with the interior of the tubular body; substantially as described.
- 20 2. A valveless two-cycle hydrocarbon-motor comprising the casing, the pipe having openings at its upper end and depending from the cover of the casing, the upper cylinder formed with supply-ports and efflux-ports, and providing a conduit-chamber and an efflux-chamber in connection with the casing, the lower cylinder having ports and of less diameter than the upper cylinder, a piston having a tubular body surmounted by a mantle, telescoping the pipe, and formed with ports adapted to coincide with the ports in the lower cylinder, and an igniting 25 means connected with the interior of the tubular body; substantially as described.

ing means connected with the interior of the tubular body; substantially as described.

25

2. A valveless two-cycle hydrocarbon-motor comprising the casing, the pipe having openings at its upper end and depending from the cover of the casing, the upper cylinder formed with supply-ports and efflux-ports, and providing a conduit-chamber and an efflux-chamber in connection with the casing, the lower cylinder having ports and of less diameter than the upper cylinder, a piston having a tubular body surmounted by a mantle, telescoping the pipe, and formed with ports adapted to coincide with the ports in the lower cylinder, and an igniting means connected with the interior of the tubular body; substantially as described.

30

The foregoing specification signed at Berlin this 30th day of March, 1898.

FRITZ DÜRR.
